(57) CLAIM

I claim the ornamental design for a spider figurine, as shown
and described.

DESCRIPTION

FIG. 1 is a frontal perspective view of the spider figurine
according to the present design;

FIG. 2 is a rear perspective view according to the present
design;

FIG. 3 is a front view of the present design;

FIG. 4 is a rear view of the present design;

FIG. 5 is a top view of the present design;

FIG. 6 is a right side view of the present design, a corre-
sponding left side view being a mirror image thereof; and,
FIG. 7 is a bottom view of the present design.
